UNITED STATES PATENT OFFICE.

CHARLES RUBY MOORE, OF MAPLEWOOD, NEW JERSEY, ASSIGNOR TO WESTERN ELECTRIC COMPANY, INCORPORATED, OF NEW YORK, N. Y., A CORPORATION OF NEW YORK.

TELEPHONE TRANSMITTER.

Application filed October 3, 1921. Serial No. 505,060.

To all whom it may concern:

Be it known that I, CHARLES RUBY MOORE, a citizen of the United States, residing at Maplewood, in the county of Essex, State of New Jersey, have invented certain new and useful Improvements in Telephone Transmitters, of which the following is a full, clear, concise, and exact description.

This invention relates to telephone transmitters and particularly to transmitters employing comminuted material as the current varying medium.

The object of the invention in general is to provide a highly efficient and economical transmitter having a high resistance path through a comminuted material, whereby the transmitter may be operated directly across a voltage of a commercial telephone circuit.

In accordance with the general features of this invention there is provided a construction in which the marginal walls of the carbon containing chamber form electrodes and a barrier located between the electrodes and extending transverse of the chamber insulates them from each other except through the conducting path formed by the comminuted material, thereby providing a comparatively long path for the passage of current between adjacent electrodes.

In its preferred form the chamber for the comminuted material is cylindrical and sufficient comminuted material is provided therein so that regardless of the position in which the transmitter may be held, the circuit through the comminuted material cannot be opened.

In the drawing, Fig. 1 is a sectional elevation of a transmitter embodying the invention.

Fig. 2 is an exploded view showing the parts of the transmitter disclosed in Fig. 1.

Figs. 3 and 4 illustrate applications of the invention to an inertia type transmitter and a repeater respectively.

In Fig. 1 casing 1 serves to inclose the working parts of the transmitter and to support a face plate 2 which in turn carries a mouth-piece 3. A diaphragm 4 is supported against the face plate, and a bridge member 5 also carried by the face plate serves to support the granular containing chamber 6.

In Figs. 1 and 2 the granular containing chamber is of circular cup-like form. Annular electrodes 7 and 8 of brass or other

suitable conducting material are mounted on the marginal walls of the chamber and insulated therefrom. Separating the electrodes is a washer shaped barrier 9 of insulating material having a central opening through which the current between the electrodes must pass. In the back of the chamber and insulated therefrom is a plate 10 to which a rod 11 forming one electrode terminal is attached. The face of this plate is coated with insulating material except near the edge where it makes contact with the electrode 7. Securing the electrodes and the barrier in place is a clamping ring 12 threaded to the cup 6. A flexible cover, diaphragm 14, is secured by a similar ring 13. Supported in the center of the closure is a plunger 15 which is provided with a stud 16 by means of which vibrations of the main diaphragm 4 are transmitted to the diaphragm 14. The plunger is held against the diaphragm 4 by a spring 17.

It is evident that the co-axial arrangement of a pair of annular electrodes forming the marginal wall of the carbon chamber and separated by an insulating ring, as shown in the drawings, provides a transmitter in which friction between the electrodes and the carbon particles is minimized.

In Fig. 3 the transmitter button is supported entirely by a diaphragm 18 to which it is attached by means of a stud 21 connected to a plunger 20, and a nut 19. To reduce the sensitivity of the device to vibrations other than those in the direction of the movement of diaphragm 18, that part of the button forming the electrode containing chamber 25 is balanced by the member 26 attached to the outer wall 22 of the chamber and extending on the opposite side of the supporting diaphragms 23 and 24.

In Fig. 4 the barrier 27 is integral with electrode 28 and rear wall 29 is integral with electrode 30. All parts except the marginal surface of the electrodes where contact with the granular material is desired are insulated.

The two most serious defects in transmitters of the granular carbon type are their susceptibility to burning and packing. These defects, which are inherent in the structures of former types of transmitters, have precluded their most economical use in the present telephone systems and have rendered them quite unsatisfactory for use.

in systems employing comparatively high voltages, for example 48 volt common battery systems or those in which a considerable power must be transmitted. The principal cause of burning is the heat generated by the comparatively high voltage caused by the high resistance contacts developed between the electrodes and the carbon granules due to their tendency to separate when agitated. Packing is due to the heating action of the current and the crowding together of the granules. In the former types of transmitters this resulted in the lower layers of the carbon mass, where the agitation is the least, carrying most of the current.

Transmitters embodying the features of the structure herein described eliminate direct action between the carbon granules and the electrodes. Therefore, the resistance at this point remains substantially constant and any tendency which there may be toward packing will not shunt the current from the path of maximum agitation. By lengthening the path through the comminuted material, minimizing relative movement between the electrodes and the granules thereby minimizing friction and directing the current through the area of maximum agitation, a transmitter button is produced whose resistance is relatively high in comparison with transmitters heretofore known.

In the illustrations used for the purpose of describing the invention only two electrodes have been shown. It is obvious, however, that three or more electrodes similarly disposed with barriers between adjacent electrodes may be used.

40 What is claimed is:

1. A transmitter comprising an electrode chamber, a pair of annular electrodes disposed in the marginal wall of said chamber, and an annular insulating barrier between said electrodes projecting into the interior of said chamber.

2. A transmitter comprising an electrode chamber, a pair of annular electrodes, an annular insulating barrier between said electrodes, the inside diameter of said barrier being smaller than the inside diameter of either electrode.

3. A transmitter comprising an electrode chamber, an annular partition dividing the chamber into two parts, an annular electrode forming the marginal wall of each part, and comminuted material forming a conducting path between said electrodes through an opening in said partition.

4. A transmitter comprising an electrode chamber, a pair of annular electrodes disposed in the marginal wall of said chamber, a partition dividing the chamber into two parts and insulating the electrodes from each other, comminuted conducting material

connecting said electrodes, and means having movement parallel to the faces of the electrodes for agitating the comminuted material.

5. A telephone transmitter comprising an electrode chamber, a pair of annular electrodes co-axially disposed therein, comminuted material connecting said electrodes, and a barrier for concentrating the current flow through said material at the center of the chamber.

6. A telephone transmitter comprising an electrode chamber, a pair of annular electrodes co-axially disposed therein, comminuted material connecting said electrodes, and means for concentrating the current flow through said material at the center of the chamber, said means comprising an annular insulating member having an open therethrough.

7. A telephone transmitter comprising an electrode chamber, a plurality of co-axially disposed annular electrodes forming the marginal wall of said chamber, current conducting material connecting said electrodes, means for agitating said material, and a barrier covering the adjacent plane surfaces of said electrodes for concentrating the current through said material at the central area of maximum agitation in said chamber.

8. A telephone transmitter comprising an electrode chamber, annular electrodes disposed in the wall of said chamber, a flexible closure for said chamber, comminuted material agitated thereby, and an insulation washer between said electrodes for concentrating the current flow at the area of maximum agitation.

9. A transmitter comprising a chamber, a plurality of annular electrodes forming the marginal wall of said chamber, a perforated insulating barrier transverse of said chamber between adjacent electrodes, and comminuted material connecting said electrodes through the perforation in said barrier, the ohmic resistance of the path through said comminuted material being comparatively high.

10. A telephone transmitter comprising an electrode chamber, electrodes rigidly mounted therein to form the side walls of the chamber, means for insulating said electrodes from each other, granular material connecting said electrodes, a plunger for actuating said material and to form a part of the chamber wall, the electrodes being so mounted with respect to said plunger that friction between the granules and the electrodes is minimized.

11. A telephone transmitter comprising an electrode chamber, a pair of electrodes insulated from each other and forming the side walls of said chamber, a stationary back wall, a diaphragm forming the front wall, granular material in said chamber forming

a variable resistance medium between said electrodes, the electrodes being so mounted with respect to the active parts of the dia-phragm that friction between the granules and the electrodes is minimized.

12. A transmitter comprising an electrode chamber, a plurality of co-axially disposed annular electrodes disposed in the side walls

of said chamber, conducting material in said chamber, connecting said electrodes, and a 10 perforated insulating member within said chamber between said electrodes.

In witness whereof, I hereunto subscribe my name this 29th day of September, A. D. 1921.

CHARLES R. MOORE.
